UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed June 11, 1921. Serial No. 476,768.

To all whom it may concern:

Be it known that I, GEORGE A. SEIB, citizen of the United States, and resident of Ilion, in the county of Herkimer and State 5 of New York, have invented certain new and useful Improvements in Typewriting Machines, of which the following is a specification.

My invention relates to typewriting machines and more particularly to accent writing means.

The main object of the invention, generally stated, is to provide simple and efficient means of the character referred to and yet 15 obtain plenty of room in the type basket for the accent type-bars or blocks.

It has been found to be desirable to provide means whereby a letter to be accented may first be written and then after a letter- 20 space movement of the platen to add an accent mark above or below said letter with the aid of a "dead key," or one which may be actuated to print an accent mark without effecting a feed of the carriage. It has also 25 been found desirable to provide for writing an accent character with both upper and lower case types so that fewer accent keys may be required in a keyboard. However, certain practical difficulties have been en- 30 countered to the attainment of these ends (especially in a machine of the general character in which my invention is shown embodied) but these I have overcome, as will hereinafter more clearly appear.

To the above and other ends which will hereinafter appear, my invention consists in the features of construction, arrangements of parts and combinations of devices set forth in the following specification and particularly pointed out in the appended claims.

In the accompanying drawings, wherein like reference characters indicate corresponding parts in the various views,

Figure 1 is a fragmentary fore-and-aft 45 central vertical sectional view, with parts omitted, of an improved No. 10 Remington machine embodying my invention.

Figure 2 is a detail fragmentary front view of the segment and some of its associated parts, the view showing the left-hand accent type bar at the printing point.

Figure 3 is a like view showing the right-hand accent type bar at the printing point.

Figure 4 is a detail fragmentary plan view partly in section and showing the two

extreme left-hand type bars of the series as they appear when at rest in the basket.

Figure 5 is a like view of the two extreme right-hand type bars.

Figure 6 is a fragmentary front view of a 60 segment slotted to receive two accent type bars at the right-hand end of the series.

Figures 7 and 8 are views of the left-hand and right-hand accent keys respectively.

Figure 9 is a representation of the different accent marks written as they appear over accented letters and in each instance after the letter is written.

The frame of the machine comprises a 70 base 1, corner posts 2 and a top plate 3, over which latter a carriage (that carries a platen 4) is adapted to travel from side to side of the machine under control of the usual escapement. The escapement is not 75 shown but will be understood to be controlled in the usual manner by a segmental universal bar 5, actuated by a contact 6 on each of the ordinary type bars 7. Motion is transmitted from said type bars 7 to the 80 universal bar to move the latter rearwardly and, through the arms 8 and 9, rock a shaft 10 and transmit a rearward movement from a centrally disposed arm 11 on said shaft to a link 12 which operates the carriage es- 85 capement, as disclosed in the patent to Oscar Woodward, No. 1,342,489, dated June 8, 1920.

The various segmentally arranged type bars are mounted in guide or bearing slots 90 in a type bar segment 13 and on a pivot wire 14 which is arranged in an arc; the type bars moving upwardly and rearwardly to strike against the front face of the platen 4. In moving to the printing position each 95 type bar enters between the jaws of the usual center guide 15. In the present instance I have shown a type bar segment having forty-four guide slots. In the specific construction shown the first forty-three of these slots, counting from left to right, and all of which except the first are indicated by the reference numeral 16, are radially disposed; all radiating from a common point, as indicated by the dotted lines α and α' in 100 Fig. 3. The body portions of all of the bars mounted in these radial slots move in radial planes corresponding to said slots. The right-hand terminal slot 18, however, is cut in a non-radial plane, indicated by the 110

dotted line *b* in Fig. 3. It will be seen that the upper end of the line *b* is, in the present instance, about $\frac{1}{10}$ of an inch below the point of convergence of the lines *a* and *a'*, the line *a* representing the plane of the left-hand terminal radial slot 17, for purposes which will hereinafter appear. In the present instance I utilize the terminal radial slot 17 at the left-hand end of the series and the 10 non-radial slot 18 at the right hand of the series in which to mount respectively the two type bars 19 and 20 which are to write the accent marks. It should be understood however that a greater or less number of 15 such accent bars may be provided, as will presently appear. Each accent type bar in the present instance carries a type block 21 with two accent types 22 thereon, one in the upper case position and the other in the 20 lower case position, so that each type bar may print an accent mark in each case position. Each of the accent bars is bent laterally at its point of convergence, as indicated at 23, like the corresponding bends in the 25 ordinary side type bars 7 so as to properly enter the type guide 15. However, the type bar 20 in addition has two extra bends, or a double bend as indicated at 24 and 25, so as to off-set its type block to write with either 30 type a letter space to one side of the normal printing point, as indicated by the dotted line *c* in Fig. 3. In the present instance this off-setting is to the left of the ordinary or normal printing point at which the type 35 bars 7 strike, and which is indicated by the dotted line *d* in Fig. 3. Of course, if the entire type system travels relatively to the platen, as in a flat platen machine, the off-setting of the type would be to the right of 40 the ordinary printing point; the object being in each instance to write the accent mark above or below a previously written letter, as indicated in Fig. 9, immediately the carriage has completed its letter space movement 45 after writing such letter.

This off-setting of the type block on the type bar 20 has heretofore presented the difficulty or objection that in the ordinary construction there would not be sufficient room 50 for it in the basket when said bar returns to its position of rest, represented in Fig. 5, and it would collide with the adjacent type bar 7. It is to avoid this difficulty that I cut the slot 18 of the accent type bar 20 in a 55 non-radial plane *b* and bend the type bar. After the bar is mounted in its slot the shank or body portion thereof is bent laterally at 20° from the plane of the slot (indicated by the dotted line *b*) to the full line 60 position of the bar represented in Fig. 3, so as to bring the type thereon in proper position with reference to the printing line and enable the bar to properly enter the type guide; the body portion of the bar converging 65 to the same point as the bars mounted

in the radial slots. When the type bar 20 returns to rest in the basket the body portion thereof flares away from the adjacent bar 7, as indicated in Fig. 5, thus providing ample room in the basket for the type bar 70 20 and its type block.

The left-hand accent bar 19 has a double bend 24 and 25 to off-set the type block to print a letter space to the left of the ordinary printing point, as indicated by the 75 dotted lines *c*, *d* in Fig. 2, precisely as in the case of the right-hand bar 20. However, on inspection of Fig. 4 it will be seen that this off-setting of the type block on the bar 19 instead of bringing it closer to the adjacent 80 bar 7 in the basket, as in the case of the type bar 20, carries it away from the block of the adjacent bar. Therefore, there is sufficient room in the basket for the type bar 19 and it is unnecessary, in this instance, to make its 85 bearing slot non-radial and bend the body portion of the bar laterally with reference to the plane of its slot, as in the case of the bar 20.

The means for actuating the type bars 90 may be of any suitable construction. In the present instance, they are the means employed in the improved No. 10 Remington machine and consist of spring returned key levers 26 fulcrumed on a bar 27 and each 95 provided with a finger key 28; the finger keys of the left and right-hand accent bars being represented respectively in Figs. 7 and 8. Each key lever is pivoted at 29 to a sub-lever 30 that is fulcrumed at 31 and 100 carries a laterally projecting headed pin 32 at its upper end. Each pin 32 enters a slot 33 of the companion type bar and by a depression of the companion key the type bar is moved to printing position. 105

As hereinbefore indicated, each of the ordinary type bars 7 during a printing operation actuates the universal bar 5 and the escapement mechanism controlled thereby and effects a letter feed of the carriage. 110 However, in order that each of the accent bars 19 and 20 may operate to print without effecting a feed of the carriage, I cut away the contact 6 on each bar, as indicated by the notch 34 in the heel thereof. Therefore, 115 each of the accent bars 19 and 20 is inoperative on the universal bar 5. It is necessary, however, when using the ribbon vibrator 35 to actuate it at each operation of an accent key, as well as at an actuation of each of the 120 ordinary printing keys. I therefore provide an independent universal bar 36 for actuating the ribbon vibrator. This universal bar extends beneath the key levers and is acted on by a projecting finger 37 carried 125 by each accent key lever, as well as by each of the key levers of the ordinary actions. The universal bar 36 is carried by arms 38 connected with a rock shaft 39. This shaft is provided with an upright arm 40 slotted 130

at its upper end, as at 41, to receive a grooved roller 42 carried by a rod 43 supported between depending arms 44 of an actuating frame. This frame is pivoted at 45 to a fixed part 46 of the machine, and is operatively connected by the usual means (not shown) to the ribbon vibrator, substantially as represented in my Patent No. 1,203,795, dated November 7, 1916. It will be understood, therefore, that at each operation of an accent key as well as at each operation of a key lever of an ordinary type action, the vibrator will be elevated to bring the ribbon into the path of the type on the accentuated type bar.

It will be seen that, if desired, the accent type bar 19 may be replaced by an ordinary bar 7. If, on the other hand, it be desired to provide more than four accent types, one or more additional non-radial slots may be provided at the right-hand side of the segment in which to mount accent type bars somewhat like the type bar 20. Thus, from an inspection of Fig. 6 it will be seen that the slot 47, second from the right-hand end of the series, is cut in the non-radial plane indicated by the dotted line ϵ , and that the upper end of this line is about $\frac{1}{16}$ of an inch below the point of convergence of the planes of the radially disposed slots, indicated by the upper ends of the dotted lines a , a' and f . In Fig. 6, the extreme right-hand end slot 48 is, however, cut on a plane represented by the dotted line g , the upper end of which is about $\frac{1}{16}$ of an inch below the point of convergence of the planes of the radial slots. By slotting the segment in this manner and bending the two bars received in the two right-hand non-radial slots 47 and 48 laterally of said planes as previously described, room is provided in the basket for off-setting the type blocks on two right-hand accent bars such as 20.

From the foregoing description it will be understood that I have provided simple and efficient dead key mechanism while providing ample room in the basket of a front strike or visible machine for the desired number of type bars having off-set accent type blocks.

In a companion application filed June 3, 1921, Sr. No. 474,700, I have included claims which dominate certain features of the present invention; claims of the present case being restricted to features not disclosed in said companion application.

What I claim as new and desire to secure by Letters Patent, is:—

1. In a typewriting machine, the combination of a type bar actuated universal bar for the escapement, an accent writing type bar inoperative at all times on said universal bar and provided with two accent types thereon, one in upper case position and the

other in lower case position and both of which types are offset to print a letter space distance to one side of the ordinary printing point, a ribbon vibrator, and an independent key-lever actuated universal bar for the ribbon vibrator which is actuated by an operation of the key lever of the accent type bar as well as by an actuation of the key levers of the other type bars.

2. In a typewriting machine, the combination of a series of type bars, a segment having radial bearing slots in which said type bars are mounted and also having a non-radial bearing slot, and an accent writing type bar mounted in said non-radial slot and having an accent type offset to write one letter space from the ordinary printing point.

3. In a typewriting machine, the combination of a series of segmentally arranged type bars, and a center guide therefor; a terminal type bar of the series having an accent type offset thereon to write a letter space distance to one side of the ordinary printing point, said terminal type bar having a double bend therein where it extends above the guide in order to effect such offsetting of the type.

4. In a typewriting machine, the combination of a series of type bars, a segment having radial bearing slots in which said type bars are mounted and also having a non-radial bearing slot, an accent writing type bar mounted in said non-radial slot and having its body portion bent laterally with reference to the plane of said non-radial slot; said accent writing type bar having an accent type block offset to write one letter space to one side of the ordinary printing point.

5. In a typewriting machine, the combination of a series of type bars, a segment provided with radial bearing slots in which said type bars are mounted and also provided with a non-radial bearing slot, an accent writing type bar mounted in said non-radial slot and having a type offset thereon to write a letter space to one side of the ordinary printing point, and a pivot wire formed in an arc and on which all of said type bars are pivoted.

6. In a typewriting machine, the combination of a segment having radial bearing slots and a terminal non-radial bearing slot, type bars mounted in said slots, the type bar mounted in the non-radial slot being an accent writing bar with an offset type to print a letter space to one side of the ordinary printing point, and a center guide for the type bars, the accent bar having a double bend therein where it extends above said guide in order to effect said off-setting of the type.

7. In a typewriting machine, the combination of a series of type bars, a segment having radial type bar bearing slots extending

- to one terminal and also having a non-radial type bar bearing slot at the other terminal; the type bar mounted in the radial terminal slot being an accent writing bar with its 5 type offset to print one letter space from the normal printing point, and the type bar mounted in the non-radial terminal slot being also an accent writing bar and having its type offset to write one letter space from 10 the normal printing point.
8. In a typewriting machine, a series of segmentally arranged type bars, a terminal type bar of the series having an accent type offset thereon to write a letter space distance 15 to one side of the ordinary printing point, said terminal type bar having a double bend therein at its type-carrying end.
9. In a typewriting machine, the combination of a series of type bars, a segment having radial bearing slots in which said type bars are mounted and also having at one 20 terminal a non-radial bearing slot, the type bar mounted in the radial terminal slot being an accent writing bar with two accent 25 types one for writing in the upper case position and the other in the lower case position, both types being offset to write one letter space from the ordinary printing point, and the type bar mounted in said non-radial terminal slot being provided with two 30 accent types one for writing in the lower and the other in the upper case position and both being offset to write one letter space to one side of the ordinary printing point. 35
10. In a typewriting machine, the combination of a type bar segment having radial slots and also a non-radial slot, a series of type bars pivotally mounted to swing in said radial slots, and an accent type bar mounted to swing in said non-radial slot; 40 said type bar having a bend in its shank as at 20° and bends 23, 24 and 25 at its type bearing end.
- Signed at Ilion, in the county of Herkimer and State of New York this 9th day 45 of June, A. D. 1921.
